[57] CLAIM

The ornamental design for a kitchen range hood, as shown and described.

DESCRIPTION

FIG. 1 is a perspective view of our design for a kitchen range hood in accordance with our invention, showing the left side, top and front thereof;

FIG. 2 is a top plan view thereof;

FIG. 3 is a front elevational view thereof;

FIG. 4 is a right side elevational view thereof, with the left side being a mirror image;

FIG. 5 is a bottom plan view thereof;

FIG. 6 is a rear view thereof;

FIG. 7 is a cross-sectional view taken along line 7—7 of FIG. 2;

FIG. 8 is a cross-sectional view taken along line 8—8 of FIG. 2; and,

FIG. 9 is a cross-sectional view taken along line 9—9 of FIG. 2.

The broken-line showing of environmental structure in FIGS. 1, 2, 4, and 5 is for illustrative purposes only and forms no part of the claimed design.
